UNITED STATES PATENT OFFICE

2,655,063

DRIVE MEANS FOR DOUBLE-ENDED
SOCKET WRENCHESVirgil P. Carrick and Walter B. Cates,
High Point, N. C.

Application October 13, 1952, Serial No. 314,432

4 Claims. (Cl. 81—57)

1

This invention relates to new and useful improvements and structural refinements in tools, and the principal object of the invention is to provide means whereby tools such as screw drivers, wrenches, etc., may be quickly, easily and expeditiously rotated.

The above object is achieved by the provision of what may be called a rotary actuator which is equipped with sockets to selectively receive a variety of different tools, an important feature of the invention residing in the provision of means for rapidly rotating a drive unit of the actuator to which the tools are connected.

Another feature of the invention resides in the provision of means for locking the drive unit to its housing so that the actuator may be turned in a comparatively slow manner by hand, such as for example, in the initial stage of loosening or the ultimate stage of tightening screws, bolts, or the like.

Some of the advantages of the invention reside in its simplicity of construction, in its efficient and dependable operation, and in its adaptability to economical manufacture.

With the above more important objects and features in view, and such other objects and features as may become apparent as this specification proceeds, the invention consists essentially of the arrangement and construction of parts as illustrated in the accompanying drawings, in which:

Figure 1 is a perspective view of the invention in use.

Figure 2 is a group perspective view thereof.

Figure 3 is a vertical sectional view of the invention.

Figure 4 is a cross-sectional view taken substantially in the plane of the line 4—4 in Figure 3.

Figure 5 is a cross-sectional view taken substantially in the plane of the line 5—5 in Figure 3, and

Figures 6, 7 and 8 are perspective views of various tools such as may be used in connection with the invention.

Like characters of reference are employed to designate like parts in the specification and throughout the several views.

Referring now to the accompanying drawings in detail, the invention consists of a rotary tool actuator which is designated generally by the reference character 10 and embodies in its construction a substantially cylindrical housing 12 which has open ends provided with in-turned annular flanges 14 functioning as retainers for a pair of anti-friction bearings 16 which are mounted in the end portions of the housing.

2

The housing 12 also accommodates a rotatable drive unit designated generally by the reference character 18, the same including a pair of end members 20, 22, which are formed integrally with cylindrical adapters 24, the latter having polygonal bores 26 to receive a polygonal shank 28.

The adapters 24 are in abutment and transverse pins 32 extend through the adapters and through the shank 28 so as to hold the end members 20, 22 together.

The end members 20, 22 are provided with races 29a, 22a respectively, which are engaged by the aforementioned bearings 16 so as to rotatably sustain the entire drive unit 18 in the housing 12.

It is to be observed that the end members 20, 22 project slightly through the open ends of the housing and are formed with polygonal sockets 34 to receive in an interchangeable fashion removable tools 36, 38, 40, etc., which are held in the sockets by spring pressed keeper elements 42 of any conventional type.

A spool 44 is slidably and rotatably positioned on the adapters 24 of the drive unit 18 and is formed integrally with an over running clutch member 46 which is engageable with a coacting clutch member 48 provided on the end member 22. A spring pressed pin 50 carried by the end member 20, slidably engages a groove 54 formed in one end of the spool 44, whereby to urge the spool toward the member 22 so that the clutch members 46, 48 are in engagement. The spring associated with the pin is shown at 56 and it will be noted that the pin 50 is substantially parallel to the longitudinal axis of the drive unit 18 so as to function in the manner described.

A resilient, flexible tape 58 is windable on the spool 44 to which it is secured at its inner end by a screw 60, the outer end of the tape 58 projecting outwardly through a lateral opening or slot 62 with which the housing 12 is formed. A grip 64 is provided at the outer end of the tape 58 and it is to be understood that the resiliency of the tape is such as to normally cause the same to wind itself upon the spool 44.

However, when the tape 58 is pulled outwardly from the housing rapid rotation is imparted to the entire drive unit 18 and to the tools 36, 38, 40, or the like, such as may be connected to the drive unit. The arrangement of the over-running clutch 46, 48 is such that when the tape 58 is pulled outwardly from the housing, rotation of the spool 44 is transmitted through the clutch to the drive unit 18. However, when the tape 58 is released and is permitted to wind itself back upon the spool 44, the clutch member 46 merely skips 55 over the clutch member 48 without imparting any

rotation to the drive unit. In that manner, unidirectional rotary movement is imparted to the drive unit by successive outward and inward movement of the actuating tape, as will be readily understood.

Of course, when the work such as for example, a bolt head or a nut illustrated at 66 in Figure 1, is to be tightened, it is engaged by the tool at one end of the device, and when the bolt or nut is to be loosened, the device is simply inverted so as to rotate the work in the relatively opposite direction.

Means are provided for initial loosening or ultimate tightening of the work by comparatively slow, hand effort, that is, by rotating the housing 12 together with the drive unit 18 as a unit, without actuating the tape 58. These means involve the provision of a plurality of locking pins 68 which are mounted on resilient fingers 70 secured by rivets 72 to the housing 12 at the outside of the latter, the locking pins 68 projecting through suitable apertures 14 into the housing and being receivable in blind, radial bores 76 in the end member 22 of the drive unit.

Thus, when the housing 12 is gripped by the hand so as to press the fingers 70 inwardly, the pins 68 are received in the apertures 76 and the entire drive unit 18 is locked against rotation in the housing so that it may be turned by hand in unison with the housing when substantial torque is to be applied to the work.

To facilitate assembly of the device, the housing 12 is preferably composed of two complementary sections 12a, 12b, which are separably connected together by suitable screws 18.

It is believed that the advantages and use of the invention will be clearly understood from the foregoing disclosure and accordingly, further description thereof at this point is deemed unnecessary.

While in the foregoing there has been shown and described the preferred embodiment of this invention it is to be understood that minor changes in the details of construction, combination and arrangement of parts may be resorted to without departing from the spirit and scope of the invention as claimed.

Having described the invention, what is claimed as new is:

1. A rotary tool actuator comprising a sub-

5

stantially cylindrical housing constituting a handle, said housing having open ends and being provided with a lateral opening, an elongated drive unit rotatably mounted in the housing and provided at the ends thereof with tool receiving sockets projecting through the open ends of the housing, a spool rotatably mounted intermediate the ends of said drive unit, a resilient actuating element wound on said spool and projecting outwardly from the housing through said opening, and an over-running clutch operatively connecting said spool to said drive unit for rotating the latter when said element is pulled outwardly from the housing.

2. The device as defined in claim 1 wherein said spool is slideable as well as rotatable on said drive unit, said overrunning clutch comprising a clutch member provided on said spool, a coacting clutch member provided on said drive unit, and resilient means for sliding said spool to a position wherein the clutch members are in engagement.

3. The device as defined in claim 1 wherein said drive unit comprises a pair of end members having said sockets provided therein, a pair of abutting cylindrical adapters provided on the respective end members, and a coupling shank disposed axially in and securing said adapters together, said spool being slidably and rotatably positioned on said adapters.

4. The device as defined in claim 1 together with means provided on said housing and engageable with said drive unit for locking the latter against rotation in the housing.

VIRGIL P. CARRICK.
WALTER B. CATES.
